UNITED STATES PATENT OFFICE.

GEORGE W. ELWELL AND BERNARD FAY, OF DANBURY, CONNECTICUT.

HAT-SIZING MACHINE.

SPECIFICATION forming part of Letters Patent No. 311,572, dated February 3, 1885.

Application filed October 10, 1884. (No model.)

To all whom it may concern:

Be it known that we, GEORGE W. ELWELL and BERNARD FAY, citizens of the United States, residing at Danbury, in the county of 5 Fairfield and State of Connecticut, have invented certain new and useful Improvements in Hat-Sizing Machines; and we do hereby declare the following to be a full, clear, and exact description of the invention, such as will 10 enable others skilled in the art to which it app pertains to make and use the same.

Our invention relates to the class of hat-sizing machines in which the bundles of hat-bodies are rolled along through chambers by 15 means of endless aprons; and the object there- of is to simplify and improve their construction, to produce, in short, a machine which shall be economical in cost, durable, and prac- tically impossible to get out of order. With 20 these ends in view we have devised the im- proved construction, which we will now de- scribe in connection with the accompanying drawings, forming part of this specification, in which similar letters indicate like parts in 25 all the figures.

Figure 1 is a longitudinal section on the line xx in Fig. 2; Fig. 2, a transverse section on the line yy in Fig. 1, excepting that the roll is shown in full lines; Fig. 3, a side elevation 30 of the entire machine; and Fig. 4, a plan view of the belt, a portion of the cross-pieces being removed, and also showing two of the rollers which support the belt.

A A represent the frame-work of the ma- 35 chine, which may be put together in any suit- able manner, and may be made of either metal or wood, the latter, however, being deemed preferable.

B is the trough, and C the table.

40 D represents hexagonal rollers, whose shafts are journaled in the corner-posts of the ma- chine, and E round rollers, whose shafts are journaled in the intermediate posts.

F and G represent, respectively, the roof 45 and bottom of the machine, both of which are made adjustable up or down in any suitable manner. We preferably, however, use ad- justing-shafts having gears which mesh with racks upon the top and bottom, as shown in 50 our former Patent No. 306,598, granted Octo- ber 14, 1884.

An important feature of our present inven-

tion consists in an endless wooden apron car- 55 ried by the rollers. This apron consists of bands or independent belts H, of metal, rub- ber, leather, or any suitable material, to which cross-strips H', of wood (metal may be used, if preferred) are bolted or otherwise firmly secured. Any number of these belts may be used; but we preferably use three only, mak- 60 ing them about three inches in width, and placing one at each edge of the rollers and one midway between them. These strips are preferably made about three inches wide, and are placed close together and bolted to the 65 belts, after which the heads of the bolts are riveted to give additional security.

In our present machine, as in the one de- 70 scribed in our patent referred to above, we make both roof and bottom concave in outline, and provide them with ribs or lags F'G', the size, location, and arrangement of which are matters wholly within the judgment of the person con- structing the machine. The cross-strips H' are made concave in outline from end to end, 75 the curvature corresponding in every respect with that of the top and bottom, thus forming two concave chambers, M. The cross-strips are also provided with lags H'', which corre- 80 spond in size, number, and arrangement with those upon the top and bottom. In the pres- ent instance we have shown each cross-strip as provided with five lags. As stated above, however, this is a matter wholly within the judgment of the constructor. We have shown 85 the inner rollers as straight round ones, and the two end ones as hexagonal in cross-section. This, however, is not an essential feature of our invention, as straight round rollers may be used at the ends, if desired. We preferably, 90 however, at the ends use some form of roller which is polygonal in cross-section, making the width of the sides to correspond with the width of the cross-pieces of the apron, so that when in use each of the sides of the end rollers 95 will carry one cross-strip of the apron, thus preventing the possibility of the belts shift- ing or slipping on the rolls. We preferably place sliding journal-boxes in the corner-posts, in which the shafts of the two end rollers are 100 journaled. By this means we are enabled to take up the slack in the apron should it be- come stretched in use.

The gist of our present invention lies in the

two concave chambers having rigid or unyielding upper and lower surfaces or walls, both of which are provided with projections or lags, and one of which is a moving surface or wall 5 when the machine is in operation.

K represents side strips, which serve to brace and strengthen the machine, and also to close the chambers at the sides.

L represents stops, which limit the movement of the roof and bottom, so that it will be impossible under any circumstances for the lags on either to come in contact with those upon the apron.

We have shown the machine as driven from 15 a belt running on a pulley upon one of the end shafts. This shaft is additionally provided with pulleys, which carry belts running over corresponding pulleys upon the shaft at the opposite end.

20 The operation is as follows: Having adjusted the roof and bottom at equal distances from the apron, which distance will of course depend upon the class of work being done, the operator at one end of the machine dips the 25 hat-bodies in the trough, rolls them in bundles upon the table, and places the bundles upon the apron, the upper side of which, for example, moves away from him. As the apron moves along the bundles of hat-bodies are kept 30 continually rolling over and over in a direction opposite to their forward movement. The bundles are thus continually brought in contact with the ribs or lags at top and bottom of the chamber, which in effect is the same 35 as if they were subjected to a continual series of unyielding blows from above and below. After passing through the machine the hat-bodies are again dipped by another operator, rolled into a bundle, and started back again in 40 the other concave chamber—that is, the one between the apron and the bottom. This operation is repeated as many times as may be necessary to shrink the hat-bodies down to the desired size. As the bundles of bodies travel 45 forward but half as fast as the apron, they get the full thumping and beating effect of all the lags, ribs, or projections both on the top and bottom of both chambers.

Owing to the curvature of the tops and bottoms of both chambers, the bundles of bodies are kept continually in the center, so that every bundle passed through the machine must be subjected to an equal amount of manipulation. The capacity of the machine is limited 55 only by the ability of the two operators to dis-

pose of the bundles of hats. The bundles may be put in rapidly one after another, and each will receive the same amount of thumping, no matter how close they may be together.

It will of course be obvious that the details 60 of construction may be varied within reasonable limits without departing from the spirit of our invention.

We make no claim in this application to the subject-matter covered by our former Patent 65 No. 306,598; but,

Having thus described our invention, we claim—

1. A hat-sizing machine having an adjustable roof and bottom, in combination with an 70 endless apron consisting of strips placed close together and secured to belts, of metal, rubber, or any suitable material, passing over rollers, whereby unyielding chambers are formed both above and below the apron.

2. The concave roof and bottom, in combination with an endless apron consisting of concave strips placed close together and secured to endless belts passing over rollers, whereby 80 two unyielding concave chambers are formed, one wall of each chamber being stationary and the other in constant motion when the machine is in use.

3. In a hat-sizing machine, two unyielding concave chambers having lags or ribs upon 85 both walls, one of said walls being stationary, the other in constant motion, when the machine is in use.

4. The adjustable concave roof and bottom, in combination with an endless apron consisting of strips concave in the direction of their 90 length and secured to endless bands or belts, rollers which support said apron, and a polygonal roller at each end of the machine whose sides are equal in width to the width of the 95 strips, as and for the purpose set forth.

5. The adjustable roof and bottom, and the endless apron consisting of strips placed close together and secured to bands or belts, rollers which support said apron, and sliding journal-boxes which carry the end rolls, as and for the purpose set forth.

In testimony whereof we affix our signatures in presence of two witnesses.

GEORGE W. ELWELL.
BERNARD FAY.
